(57) **CLAIM**

The ornamental design for a portable electric blower, as shown and described.

DESCRIPTION

FIG. 1 is a top, front, right side perspective view of a portable electric blower, showing my new design; FIG. 2 is a bottom, rear, right side perspective view thereof; FIG. 3 is a front elevation view thereof; FIG. 4 is a rear elevation view thereof; FIG. 5 is an enlarged left elevation view thereof; FIG. 6 is an enlarged right elevation view thereof; FIG. 7 is a top plan view thereof; FIG. 8 is a bottom plan view thereof; FIG. 9 is an enlarged perspective view of a part surrounded by the two-dot chain line and labeled with 9 of FIG. 1 thereof; and, FIG. 10 is an enlarged perspective view of a part surrounded by the two-dot chain line and labeled with 10 of FIG. 2 thereof. The broken lines in the drawings illustrate portions of the portable electric blower that form no part of the claimed design. The two-dot chain lines in the drawings define the bounds of the enlarged views.
